US0D1010454S

(12) **United States Design Patent** (10) **Patent No.:** **US D1,010,454 S**
(45) **Date of Patent:** **** Jan. 9, 2024**

(54) **CONTAINER**

(71) Applicant: **GRAHAM PACKAGING COMPANY, L.P.**, Lancaster, PA (US)

(72) Inventor: **Anthony Schlies**, Lancaster, PA (US)

(73) Assignee: **GRAHAM PACKAGING COMPANY, L.P.**, Lancaster, PA (US)

(**) Term: **15 Years**

(21) Appl. No.: **29/806,558**

(22) Filed: **Sep. 3, 2021**

(51) LOC (14) Cl. **09-01**

(52) U.S. Cl.

USPC **D9/552**

(58) **Field of Classification Search**

USPC D9/499, 500, 503, 504, 505, 520, 529,
D9/540, 544, 545, 549, 550, 558, 563,
D9/574, 575, 763, 772, 559, 552, 565,
D9/779, 556, 569, 776; D7/509, 510,
D7/300, 300.1, 590, 523

CPC ... B65D 1/0276; B65D 85/72; B65D 21/0231
See application file for complete search history.

(57) **CLAIM**

The ornamental design for a container, as shown and described.

DESCRIPTION

FIG. 1 is a perspective view of the ornamental design for the container;

FIG. 2 is a front view of the ornamental design for the container;

FIG. 3 is a rear view of the ornamental design for the container;

FIG. 4 is a left side view of the ornamental design for the container;

FIG. 5 is a right side view of the ornamental design for the container;

FIG. 6 is a top view of the ornamental design for the container; and,

FIG. 7 is a bottom view of the ornamental design for the container.

The broken lines shown illustrate portions of the container and form no part of the claimed design.

1 Claim, 6 Drawing Sheets

US D1,010,454 S
